CLAIM

The ornamental design of a spinning fishing reel, as shown and described.

DESCRIPTION

FIG. 1 is a perspective view of a majority portion of one side of the fishing reel and a partial portion of the back of the reel;

FIG. 2 is a side elevation view thereof which includes the handle;

FIG. 3 is a side elevation view thereof opposite to the view shown in FIG. 2;

FIG. 4 is a top plan view thereof;

FIG. 5 is a bottom plan view thereof;

FIG. 6 is a front elevation view thereof; and

FIG. 7 is a back elevation view thereof.

FIG. 1
